James Sharkey of Brooklyn, N.Y.
Letters Patent No. 1613, dated July 29, 1862.

The schedule referred to in these Letters Patent and making part of the same.

To all whom it may concern:

Be it known that I, James Sharkey, of Brooklyn, in the County of Kings, and State of New York, have invented or produced a new and original design for a Gateway and Fence for Burial Plots; and I do hereby declare that the following is a full, clear and exact description of the same, reference being had to the accompanying drawings making a part of this specification, in which

Figure 1. is a perspective view of my design.

Figure 2. an enlarged section of one of the ornaments of the rails.

Similar letters of reference indicate corresponding parts in the two Figures.

The gate is composed of two parts A. A. hung on posts B. B. of quadrangular form and provided with or resting on a basis C. having three offsets a. a'. a''; the upper one a. having an ovol moulding b. with a fillet c. above it, the offset below a'. having a similar ovol d. and fillet e. and the lowest offset having simply an inclined upper surface f. as shown clearly in Figure 1. The posts B. have each a top surface composed of arches g. so arranged or disposed as to have a shouldered arch at each side and on the centre of each top there is a concave quadrilateral support D. on which an urn E.

Des. 1613

is placed. The supports D, at their bases are encompassed by a bead h, formed of small semi-spherical projections with an inclined or bevelled surface i, above them and a scalloped rim j, above i. At the bases of the urns G, there is a circular ornamentation formed of radial leaves k, and the bodies of the urns are covered with drapery l. The urns just below the drapery are encompassed by leaves m, which form a projecting ornament. The posts B, are provided at their front sides with raised tablets a⁺⁺.

The gate is formed of bars n, crossing each other obliquely and provided with rosettes e, at their points of intersection. The gate is provided with steps p, having balusters q, at their sides with moulded rails r, and octagonal newells F.F, in front which are surmounted by vases G, containing flowers H. The tops of the newells are provided with caps I, composed of quirked ovals beads s, and an ornamental projecting chain encompasses each newell said chain being composed of circular links t, filled each with a rosette u, and connected by horizontal bars o. The newells are provided with bases w, surmounted by a cyma-reverse bead x and a fillet y.

I, represents the rails of the fence which are of cylindrical form in their transverse section and have their ends fitted in posts J, which are of quadrilateral form at their bases and of octagonal form at their centres or between the points of junction of the rails. These posts are surmounted by balls a⁺, and the tops of the former are of concave taper form as shown at B⁺, with an inclosed upper surface c⁺, on which the balls a⁺, rest.

The rails I, are provided with a central ornament K, composed of leaf projections z⁺ on a collar or band e⁺, and having a bead f, at their outer ends and one at their centre composed of semi-cylindrical projections, and a similar ornament I, is at the ends of the rails at their junction with the posts J. The ornaments I, however are provided with an outer band h', of leaves arranged in scalloped form. The details of the ornaments K, I, are already shown in Figure 2. The rails I, which adjoin the gate posts B, are secured thereto and there are two rails between the posts of the fence as shown in Figure 1.

Having thus described my invention what I claim as new and desire to secure by Letters Patent, is—

184

Dec 16 / 3

The general configuration of the parts as herewith shown
and described to form a new and original design for a gateway, and
fence for burial plots.

Witnesses.
